UNITED STATES PATENT OFFICE.

WILLIAM STEERS, OF BRATTLEBOROUGH, VERMONT.

EXTENSION-BIT.

SPECIFICATION forming part of Letters Patent No. 296,242, dated April 1, 1884.

Application filed January 19, 1884. (No model.)

To all whom it may concern:

Be it known that I, WILLIAM STEERS, a citizen of the United States, residing at Brattleborough, in the county of Windham and State 5 of Vermont, have invented certain new and useful Improvements in Extension-Bits, of which the following is a specification, reference being had therein to the accompanying drawings.

10 This invention relates to improvements in extension-bits for boring-tools; and it consists in the employment of an adjusting tangent-screw secured in the stock, whereby the extension-blade can be easily, quickly, and accurately adjusted, all of which will be herein-after more particularly described, and pointed out in the claim.

15 In the drawings forming part of this specification, Figure 1 is a view of a center-bit, showing the ends of the extension blade or bit. Fig. 2 is another view of the center-bit, showing the face of the extension-blade and the tangent-screw detached. Fig. 3 shows the back and two ends of the extension-blade.

20 A is the shank of an ordinary center-bit, which can be fitted to the brace-socket, or it may be used with a handle, like a common auger. The screw-thread on the gimlet-point is continued around the cylindrical part B, 25 for the purpose of feeding the cutter B'.

A' is the extension-blade, of steel, having a cutting-edge, a, and lip a'.

30 On the back of the extension-blade A' is a dovetailed tongue, a'', which fits into a corresponding groove, b, in the stock A. Also, on the back of extension-blade A' are threads c, 35 cut to suit the threads on a tangent-screw, D, which is made to turn in a corresponding non-

threaded groove across the stock A. A clamp, C, is secured by a screw, D', so that when the extension-blade A' is properly adjusted the clamp C is screwed down, but not so tightened as to prevent the sliding of the extension-blade when operated by the tangent-screw D. The dovetailed groove b in the stock A keeps the tongue a'' in the other edge of the extension-blade close to the stock, to prevent the blade from springing when in the act of cutting. In the end of tangent-screw D is a slot for a screw-driver, so that by turning the tangent-screw 40 D in either direction the extension-blade A' is moved correspondingly. The tangent-screw D has a neck, e, and is secured by a pin, E, which passes through the stock and into the neck, to prevent the tangent-screw from being 45 moved endwise when turned for the adjustment of the extension-blade, which is moved endwise by means of the threads on the back, and the nicest adjustment is obtained.

I claim—

50 A center-bit stock having a continuation of the feeding-threads of the gimlet-point around the cylindrical part of the cutter, a tangent-screw secured by a neck and pin, a clamping device, and a dovetailed groove, in combination 55 with an extension-blade having on its back a dovetailed ridge, and screw-threads to match the threads of the tangent-screw, substantially as and for the purpose described.

55 In testimony whereof I affix my signature in 60 presence of two witnesses.

WILLIAM STEERS.

Witnesses:

J. G. EDDY,
H. J. BURNHAM.
